UNITED STATES PATENT OFFICE.

LEROY S. PFOUTS, OF CANTON, OHIO.

DESIGN FOR A CHANDELIER.

SPECIFICATION forming part of Design No. 33,731, dated December 18, 1900.

Application filed November 24, 1900. Serial No. 37,692. Term of patent 7 years.

To all whom it may concern:

Be it known that I, LEROY S. PFOUTS, a citizen of the United States, residing at Canton, in the county of Stark and State of Ohio, have 5 invented and produced a new and original Design for a Chandelier, of which the following is a specification, reference being had to the annexed drawing, forming a part thereof.

The figure is a side elevation showing my new design.

As shown in the drawing, the leading or material feature of my design consists of a suspending rod or bar the periphery of which is provided with a number of spiral ribs 1 and 5 grooves 2, alternating with each other. The upper end of the rod is provided with the bulb 3, which bulb is provided with a number of ribs 4, which ribs extend upward, and at their upper end is located a band 5, which 5 band is provided upon its upper portion with a series of projections 6, which are curved and terminate at the points 7, said terminating points being spaced one from the other, and between the projections are located V-shaped flanges or ornamentations 8. The projections 6 are bent or curved, as illustrated at 9.

Below the bulb 3 and upon the suspending-rod provided with the spiral rib and grooves 1 and 2 is located the bulb 10, which bulb is 5 provided with the center flange 11.

Below the center flange 11 are located the

curved tubes 12, said tubes being curved outward to the point 13 and then extended in a straight horizontal line.

Below the bulb 10 and at the bottom or lower 35 end of the rod provided with the spiral ribs and grooves is located the elongated bulb 14, which elongated bulb is provided with a center rib 15, having a flat outer surface, and below the elongated bulb 14 is located the bulb 40 16, having the center band 17, said bulb 16 also being provided with the knob 18, which knob is tapered at its upper end and provided with the flange 19.

Below the horizontal portions of the arms 12 45 are located the curved tubes 20, the convexed portions of said tubes being located face to face, and a horizontal pipe or bar extended in either direction from the elongated bulb 14 to the curved tube 20.

Having fully described my invention, what I claim as new, and desire to secure by Letters Patent, is—

The design for a chandelier, as herein shown and described.

In testimony that I claim the above I have hereunto subscribed my name in the presence of two witnesses.

LEROY S. PFOUTS.
